LAMP SHADE MOUNTING MEANS

Paul Chilo, Chicago, Ill.

Application March 12, 1938, Serial No. 195,457

2 Claims. (Cl. 240—148)

My invention relates to lamps equipped with shade supporting fixtures in the form of a harp wherein the shades may be rocked or tilted on their supports.

5 One of the objects of my invention is to provide improved mounting means on the harp for the shade and so constructed that the shade will be held securely in the desired tilted position.

It is a further object of my invention to provide 10 a device of but few parts, inexpensive to construct and assemble and which will function in combination to hold the shade in any desired tilted position on its support against the vibrations or jars to which lamps are frequently subjected when in use.

My invention preferably contemplates clamping means formed out of spring metal and it is a further object of my invention to construct the parts so that the clamping member is sprung out 20 of its initial shape when mounted on the supporting harp thereby providing a strong spring grip of the clamping member on the harp to hold the device in the desired position.

It is another object of my invention to provide 25 improved means for the purpose specified so arranged that the grip of the clamping member on the supporting means is not loosened by locking the shade in position on its support.

The preferred means by which I have accomplished 30 my several objects are illustrated in the drawings and are hereinafter specifically described. That which I believe to be new and desire to cover by Letters Patent is set forth in the claims.

35 In the drawing—

Fig. 1 is an elevational view of a lamp equipped with shade supporting means embodying the principles of my invention;

Fig. 2 is a view on an enlarged scale partly in 40 elevation and partly in section illustrating the device in position on the top of the harp-like shade support;

Fig. 3 is a sectional view taken on the line 3—3 of Fig. 2;

45 Fig. 4 is a sectional view taken on the line 4—4 of Fig. 3; and

Fig. 5 is a sectional view of the spring clamping member in association with the shade mounting stud before the clamping member is mounted 50 on the harp-like support.

Like characters of reference designate like parts in the several views.

The lamp 10 is provided with a shade support 11 which is generally in the form of a harp, the electric lamp bulb 12 being positioned within the

harp and screwed into the lamp socket in the usual manner.

My improved device comprises a clamping member in the form of a plate 13 which is provided with oppositely disposed depending arms 14. The member 13 is formed out of spring sheet metal and initially is in a shape substantially as shown in Fig. 5, the plate portion 13 being bowed and the arms 14 in positions non-parallel with respect to each other. Each of the arms 14 is provided with a sleeve-like bearing 14a preferably formed by drawing the metal into short tubes so as to afford a bearing much wider than the thickness of the metal for receiving the supporting member 11. A mounting element 15 in the form of a threaded stud is provided with a collar 16 adapted to bear against the upper face of the plate portion 13, the lower end of the stud extending through an opening 13a in the plate and then being riveted over or upset against the under side of the plate thereby providing an abutment or bearing portion 17.

In assembling the parts, the clamping member 13 is locked in a suitable fixture to bring its plate portion into substantially flat condition and its arms parallel to each other. The rigid straight wire to form the supporting harp may then be easily inserted through the bearings 14a and under the abutment 17. The clamping member is then freed from the locking fixture with the result that it tends strongly to return to its initial shape as shown in Fig. 5. The stiffness of the wire forming the supporting harp, however, holds the clamping member substantially in the position shown in Fig. 2 with the result that the clamping member takes a strong spring grip on the supporting member 11. The opposing lever grips exerted by the bearings of the arms 14 on the supporting wire 11, aided by the spring action set up in the plate portion 13, effectively prevent any slippage of the clamping member on the wire in the direction of its length, and also maintain the clamping member in the desired tilted position on the wire. The supporting member may then be put into a suitable fixture and the wire bent into the desired form and mounted on the lamp socket in any suitable manner.

A shade 18 is carried on a frame comprising a collar 19 and arms 20, the collar 19 being adapted to fit snugly around the collar 16 of the mounting stud 15. The shade is locked in position with the collar 19 bearing on the spring clamp 13 by means of a nut or finial 21 threaded on the stud 15 against the collar 19 as clearly shown in Fig. 2.

It will be apparent that the clamping means described is well adapted for its purpose. The parts are inexpensive to construct and can be readily assembled. Since the spring clamping means is sprung considerably out of its initial shape in mounting it on the supporting harp a strong spring pressure is applied to the supporting harp through the bearings 14a and the abutment 17. The relatively wide bearings 14a prevent the arms from cutting into the supporting harp which, of course, would be objectionable and tend to loosen the grip of the device on the supporting harp. It will also be noted that tightening the finial 21 on the stud 15 does not tend to loosen the grip of the clamping member on the supporting harp. The collar 16 serves as means to hold the shade in centered position with respect to its support.

I do not intend to limit the invention to the details of construction shown and described, except only in so far as certain of the appended claims are specifically so limited, as it will be obvious that modifications may be made without departing from the principles of the invention.

I claim:

1. In a shade supporting device for lamps, the combination of a supporting member having a rigid straight substantially horizontal portion and downwardly extending side portions, and a clamping member of spring material in the form of a yoke comprising a central bowed plate portion and spaced arms extending downwardly and outwardly from the plate portion, each of said arms having a bearing surface comprising an opening through which said straight portion extends, said plate portion having abutment means

between said arms pressing on said straight portion, said clamping member when in operative position on said straight portion having its said arms positioned between said respective downwardly extending side portions and being held substantially out of its initial bowed shape and against the spring action resulting therefrom with said abutment means pressing strongly against the side of said straight portion adjacent the plate portion and with said arms substantially parallel and with said bearing surfaces strongly pressing against the opposite side of said straight portion. 5

2. In a shade supporting device for lamps, the combination of a supporting member having a rigid straight portion circular in cross section, a clamping member of spring material in the form of a yoke comprising a central bowed plate portion and spaced arms extending downwardly and divergently from the plate portion, each of said arms having a sleeve-like bearing through which said straight portion extends, and a mounting element extending through said plate portion having shoulder means bearing against the under side thereof and forming an abutment 10 between said arms, said clamping member when in operative position on said straight portion being held with its plate portion straightened from said bowed shape and with its arms sprung into parallelism from said divergent relation whereby 15 said abutment bears strongly against the side of said straight portion adjacent the plate portion and portions of said sleeve-like bearings engage strongly the opposite side of said straight portion. 20
